ATTORNEY

UNITED STATES PATENT OFFICE.

MELVILLE MILLER, OF PITTSFIELD, ILLINOIS, ASSIGNOR TO BRUN-MILL COMPANY,
OF PITTSFIELD, ILLINOIS, A CORPORATION OF ILLINOIS.

VANITY CASE.

Application filed January 15, 1923. Serial No. 612,753.

To all whom it may concern:

Be it known that I, MELVILLE MILLER, a citizen of the United States, residing at Pittsfield, county of Pike, and State of Illinois, have invented a certain new and useful Improvement in Vanity Cases, of which the following is a specification, reference being had to the accompanying drawing, forming a part thereof.

10 This invention relates generally to toilet articles and, more particularly, to a certain new and useful improvement in toilet articles of the type or class commonly known as vanity-cases.

15 My present invention has for its chief object the provision of a vanity-case comprising a member in the form of a double-mirror functioning not only as a swingable wall movably dividing or separating the interior of the case into two main toilet-article-containing compartments, but also as a convenient reflecting-medium at one or the other of its surfaces as the contents of one or the other of the compartments of the case 25 may be selectively used.

Another object of my present invention is to provide a vanity-case which is conveniently portable and which compactly includes readily accessible compartments for 30 toilet-articles and coins.

With the above and other objects in view, my present invention resides in the novel features of form, construction, arrangement, and combination of parts hereinafter described and afterwards pointed out in the 25 claims.

In the accompanying drawing,

Figure 1 is a perspective open view of a vanity-case embodying my invention;

40 Figure 2 is a vertical transverse sectional view of the vanity-case;

Figure 3 is a fragmental horizontal sectional view showing one of the co-operating spring-catch or locking members of the vanity-case; and

45 Figure 4 is a fragmental front elevational view of the vanity-case.

Referring now more in detail and by reference characters to the said drawing, which 50 illustrates a preferred embodiment of my invention, the vanity-case is in the form of a shell made up of a pair of annularly flanged or cup-shaped members A and B oppositely disposed the one to the other and 55 hingedly fastened together for relative

swinging or pivotal movement by means comprising preferably a plurality of pintle-eyes 1 disposed upon a pintle 2. Preferably the member A is of somewhat greater depth than member B and may be properly 60 designated as the lid or top of the case, the member B being designated as the base or body of the case.

The lid A, as clearly seen in Figures 1 and 2, is adapted to provide a convenient compartment or chamber for a face-powder compact or the like 3 and powder-puff 4; and not only providing a retaining-wall for 65 the articles so disposed in lid A, but also dividing or separating the compartment of

lid A from the chamber of base B, is a member C comprising preferably a pair of circular mirrors 5—6 permanently secured together in flatwise opposed relation by means of an embracing rim 7 provided with a pintle-eye 8 also disposed upon the pintle 2, whereby the member C is also swingable relatively to both the lid A and base B. Preferably the pintle-eye 8 is suitably offset, 70 as shown in Figure 2, so that normally the mirror-member C is disposed within the chamber or compartment of lid A, as shown. The member C is, however, provided with a projecting flexible tab 9, on pulling engagement with which the mirror-member C may 75 be swung to expose the toilet-articles contained within the chamber of lid A.

10 indicates a circular plate or disk provided with a plurality of circular apertures of preferably varying diameter, and disposed at an end in such respective apertures and 80 permanently fixed to disk 10, are depending open-end cylindrical shells 11, 12, and 13, the plate 10 and its said depending shells 11, 12, and 13 being adapted to singly fit 85 within base B, as illustrated in Figures 1 and 2. The chamber of base B is thereby, in turn, divided into a plurality of additional individual compartments, one of which, preferably the largest compartment

13, being adapted to receive and accommodate a rouge-compact or the like 14, and a rouge-puff 15, and the smaller compartments 11 and 12 being adapted to receive 90 and accommodate coins of different value or denomination. To facilitate the removal of the coins from the compartments 11 and 12, each of such compartments is provided with a yieldingly compressible disk 16, the

plate or disk 10 being formed at said 95 100 105 110

partment 11 and 12 with overhanging disk and coin retaining flanges 17 suitably interrupted or cut-away to permit convenient individual removal of the contained or 5 stacked coins, as is common. At its upper margin, base B is formed with a somewhat inwardly offset suitably arcuated spring-tenon 18 adapted to yieldingly retain the plate 10 and its associate parts within the 10 chamber of base B.

Opposite the hinged-pintle 1, the case or shell members A and B are provided with co-operating spring-catch 19 and recess seat 20, whereby the lid and base members A 15 and B may be releasably locked together in closed position.

The vanity-case or shell is of such relative small size as to be very conveniently portable either in the hand or a pocket of 20 a garment and provides a compact readily accessible receptacle for coins and articles of toilet of the kind named, and it will be observed that, while normally the mirror 6 of member C is exposed on the opening of 25 the case and provides a reflecting-medium on use of the toilet-articles contained within the chamber B, the member C may be readily swung to selectively expose its companion mirror 5 and also the contents of the chamber 30 of lid A, and thus equally well provides a reflecting medium on use of the toilet articles contained within the chamber of lid A.

I am aware that minor changes in the 35 form, construction, arrangement, and combination of the several parts of my new vanity-case may be made and substituted for those herein shown and described with-

out departing from the nature and principle of my invention.

Having thus described my invention, what 40 I claim and desire to secure by Letters Patent is:

1. A vanity-case including a cup-shaped lid, a cup-shaped base oppositely disposed to the lid, the lid and base providing containing chambers for toilet articles, and means comprising a pintle for hingedly fastening the lid and base together for relative swinging movement, in combination with a combined partition and double mirror 45 member of reduced size to fit within the lid, and means comprising a pintle-eye for hingedly fastening the mirror to said pintle for swinging movement relatively to the lid and base, the pintle-eye being laterally offset 50 from the pintle for normally disposing the mirror-member within the confines of the lid and said partition and mirror-member providing a retaining wall for the toilet articles contained within the lid and also 55 providing a reflecting medium at one or the other of its surfaces on the selected use of the articles contained within the lid or base.

2. A vanity-case comprising a cup-shaped base, an apertured disk disposed within, and spaced flatwise from the bottom wall of, the base, and cylindrical shells disposed within the base and lengthwise through the apertures of the disk and providing coin and powder chambers, the bottom-wall of the 60 base forming the bottom-wall of said shells. 65

In testimony whereof, I have signed my name to this specification.

MELVILLE MILLER.
